Patented Feb. 5, 1918.

UNITED STATES PATENT OFFICE.

WYLIE McBRIDE, OF SPOKANE, WASHINGTON.

FRIEZE-BOARD MARKER.

1,255,190.

Specification of Letters Patent.

Patented Feb. 5, 1918.

Application filed May 14, 1917. Serial No. 168,437.

To all whom it may concern:

Be it known that I, WYLIE McBRIDE, a citizen of the United States, residing at Spokane, in the county of Spokane and State of Washington, have invented certain new and useful Improvements in Frieze-Board Markers, of which the following is a specification.

My invention relates to improvements in frieze board markers, and the principal object thereof is the provision of an instrument for accurately determining the proper cuts for the frieze board and scoring the board so that the same may be sawed to closely fit the sides and bottom edges of the rafters which it is intended to embrace.

A further object is the provision of a novel instrument of the foregoing character which is very compact, simple in construction, convenient to adjust, and handy to manipulate.

The several advantages of my improvements will be clearly pointed out in the following specification wherein will be set forth the details of construction and functions of the elements comprising the complete device, recourse being had to the accompanying drawings, in which—

Figure 1 discloses a rafter and a frieze board both indicated fragmentally, the latter occupying the position in which it is supported temporarily for the marking or scoring operation, and a longitudinal view of the marker showing its application to use for securing the vertical scores for the frieze board, the dash lines indicating the position of one of the elements after manipulation for the scoring operation.

Fig. 2 illustrates the method of using the device to obtain the horizontal score connecting the vertical scores so that the horizontal score will conform with the contour of the under face or edge of the rafter, the marker being shown in solid and dash lines to indicate the movement of the instrument required in the operation.

Fig. 3 is a sectional edgewise view taken through the slidable cutter for marking the vertical scores and the tongue to which the cutter is riveted.

Fig. 4 is an enlarged view showing the details of the adjustable scoring device for marking the depth and contour for the lower edge of the rafter.

Referring more particularly to the drawings in which like characters of reference

indicate like parts in the several views, the numeral 1 designates a straight-edge formed with a longitudinal slot 2, having cross-pieces 3, and provided at one end with a fixed positioning or squaring member 4. Slidably mounted in the slot 2 is a reduced, integral tongue 5 of a bar 6, the tongue having secured at its end a two-edged scorer 7 which is constructed as shown in Fig. 3, and consists of plates 8 secured to either side of the tongue 5 by rivets 9 and adapted to embrace the straight-edge sides of the slot, said plates with the cross-pieces 3 serving to guide the tongue in the slot 2. Each plate 8 has formed at one end an integral scoring edge 8' which projects outwardly at right angles to the face of the plate and in register with the adjacent edge of the straight edge.

The manner of using the scorer 7 is indicated in Fig. 1 wherein the instrument is shown set up against a rafter A and a frieze board B ready for the scorer to be drawn down across the board a sufficient distance to indicate one of the vertical cuts. The frieze board is, of course, first supported temporarily in place abutting the lower edges of the rafters which it is intended to embrace. To score the board for the cut for the opposite side of the rafter the same operation is repeated by placing the instrument in a like position on the remaining side of the rafter, the instrument being turned over so as to present its opposite face and scorer edge to the frieze board.

The outer end of the bar 6 is provided with an integral wrench-like head 10 formed with jaws 11 spaced apart the approximate thickness of the common commercial rafter so as to engage the edges of the same, the face 12 between the jaws being convex in shape as illustrated. Slidably mounted in a longitudinal slot 13 in the bar 6 is a cutting tool 14 for marking the depth and contour of the horizontal rafter cut. The tool consists of a nut 15 and a thumb screw 16, the latter provided with a centrally extending sharp pointed pin 17. The opposed faces of the nut and screw engage the bar to adjustably secure the tool in the slot. To indicate the proper score for the lower edge of the rafter the tool 14 is first positioned at a point in the slot to correspond with the depth of cut required, a linear scale 18 being provided along the slot on the bar for that purpose, and then the head 10 positioned as shown in Fig. 2. A pivotal

swinging movement of the instrument with the convex face 12 held firmly against the rafter edge and the cutter pin 17 in engagement with the face of the frieze board, 5 will serve to deeply score the board, the scope of the swinging movement being limited so as to score the board only between the vertical scores heretofore referred to. By reason of the convex shape of the face 10 12 which conforms with an arc of a true circle taken from a center X the marking for the depth cut connecting the two vertical cuts will conform with the contour of the rafter edge which it is intended to fit. This 15 is highly important where the edges of the rafters present an irregular, curved, or beveled face as, in such case, the marker will follow the contour of such face. Also, if any of the rafters which a given board is 20 intended to embrace is of less depth than the others and in consequence spaced slightly away from the frieze board, a cut of correspondingly less depth for that particular rafter will necessarily be made and an 25 accurate fit thereby assured.

Copies of this patent may be obtained for five cents each, by addressing the "Commissioner of Patents.
Washington, D. C."

In all events the several cut-out portions for a given board will be such as to fit the rafters accurately when the board is placed in position. As the cutter 14 follows the approximate grain of the frieze boards 30 a very deep cut may be made in the scoring operation, thereby allowing the cut-out portion to be knocked out after the vertical cuts have been sawed.

Having described my invention, I claim:— 35

1. An instrument of the character described, consisting of a bar, a head carried at one end of the bar having spaced jaws and an arcuate face between the jaws, and a longitudinally adjustable scoring tool 40 mounted on said bar.

2. In a marking device, the combination with a bar having a head with a convex arcuate edge forming a movable contact point, and guiding elements at the ends 45 of said edge, of a marking tool carried by the bar and co-acting with said edge as the contact point is moved.

In testimony whereof I affix my signature.
WYLIE McBRIDE.
